VISION TESTING APPARATUS

Thomas L. Hermann, Springfield, Ohio, assignor to
Bausch & Lomb Incorporated, Rochester, N.Y., a cor-
poration of New York

Filed Aug. 29, 1966, Ser. No. 3,626

Term of patent 14 years

(Cl. D57—1)

FIGURE 1 is a perspective view of the vision testing apparatus illustrating the front and top portions showing my new design, and

FIGURE 2 is a perspective view of the vision testing apparatus illustrating the rear and top portions.

I claim:

The ornamental design for a vision testing apparatus, as shown.
